CHARLES BOOZE, OF BUFFALO, NEW YORK, ASSIGNOR TO M. H. BIRGE & SONS,
OF SAME PLACE.

DESIGN FOR WALL-PAPER.

SPECIFICATION forming part of Design No. 21,961, dated November 8, 1892.

Application filed October 10, 1892. Serial No. 448,444. Term of patent 3½ years.

To all whom it may concern:

Be it known that I, CHARLES BOOZE, a citizen of the United States, residing at Buffalo, in the county of Erie and State of New York, 5 have invented and produced a new and original Design for Wall-Paper, of which the following is a specification, reference being had to the accompanying drawing, forming part thereof.

10 The leading feature of this design consists of a scroll-like ornament with a vase filled with flowers and leaves arranged in the center of the ornament and two birds perched upon said flowers. Above the vase of flowers is arranged a semicircle or festoon of flowers and leaves, tied at its ends by ribbons and attached to cornucopia-shaped ornaments on

each side of the center ornament, and small scroll-like ornaments spring from the center of the semicircle of flowers and leaves, as represented in the accompanying drawing. 20

The design is placed at regular intervals over the surface of the paper and is printed in any desired color or colors or in bronze and colors upon tinted paper of any desired color. 25

What I claim is—

The design for wall-paper herein shown and described.

Witness my hand this 7th day of October, 1892.

CHARLES BOOZE.
